UNITED STATES PATENT OFFICE

LESTER C. KIENZLE, OF SYRACUSE, NEW YORK

CURTAIN FIXTURE

Application filed September 10, 1931. Serial No. 562,116.

This invention has for its object, a curtain fixture attachable to a window frame, whereby the curtains can be pulled laterally back out from in front of the window opening and engaged with the fixture, and permanently held in such position so as not to be blown when the windows are open, or so as not to obstruct light rays either when the windows are open or closed.

10 It further has for its object, a particularly simple and efficient fixture which can be attached to either the front face of the window frame, or a side edge face thereof, and the arm thereof, which the curtain engages extends at approximately the same oblique angle in either of such positions.

The invention consists in the novel features and in the combinations and constructions hereinafter set forth and claimed.

20 In describing this invention, reference is had to the accompanying drawing, in which like characters designate corresponding parts in all the views.

Figure 1 is a front elevation of a window structure with the curtain fixture applied thereto.

Figure 2 is a plan view of the fixture.

Figure 3 is a front elevation.

Figures 4 and 5 are respectively, fragmentary sectional views through opposite sides of the window frame showing the fixture applied respectively to the left hand edge face of the frame, and the front face of the right hand side of the window frame.

35 Figures 6 and 7 are front elevations of parts seen in Figures 4 and 5.

This curtain fixture comprises generally, a base, and an arm projecting from the base at such angle that the arm projects obliquely relatively to the plane of the front face of the window frame when the base is mounted on either the side edge of the frame, or the front face of the frame. That is, the arm projects at a certain predetermined oblique angle to the window frame, say forty-five degrees, when the base is mounted on the left hand edge face of the window frame, and projects at substantially the same angle in the opposite direction when the fixture is

mounted on the front face of the right member of the window frame.

The fixtures are made up right and left, and can be mounted either on the edge faces of the window frame, or on the front faces, 55 and the curtain retaining arms will project in either case at the same oblique angle relatively to the front face of the window frame. Thus, one fixture, which for convenience, let us assume, is a left hand fixture, when

60 mounted on the left hand edge face of the window frame, becomes the right hand fixture if the fixture is to be mounted on the front face of the frame, and likewise, the right hand fixture attached to the right hand edge face of the window frame, becomes the left hand fixture if mounted upon the front

65 face of the window frame, and in all cases, the curtain retaining arm extends at approximately the same oblique angle relatively to 70 the front face of the frame.

1 designates the base which is attachable in any suitable manner, as by screws 2 to the edge face 3, or the front face 4 of a window frame 5.

75 6 is a curtain retaining arm pivoted to the base plate on a horizontal axis extending at an oblique angle to the general plane of the base plate, usually an angle of approximately forty-five degrees. As here illustrated, the arm 6 is mounted on a pivot 7 located in bearings provided in upright lugs 8 projecting from a horizontal bearing surface on the base 1, this bearing surface being preferably provided on an angularly extending flange or shelf 9. 80

The arm 6, when not in use, may be folded upwardly along side of the frame, as indicated in dotted lines Figures 6 and 7, and it is pivoted to the base 1 by a stop joint which prevents it from being folded downwardly 85 farther than horizontal position or any other predetermined angle. The arm 6 is here shown as formed with a stop shoulder 11 for engaging the edge of the shelf 9. By reason of the angular arrangement of the pivot 7 relatively to the base plate 1, the fixtures may be mounted either on the edge face 3 of the frame as shown in Figures 4 and 6, or on the front face of the frame, as shown 90 in Figures 5 and 7, and the curtain retaining 95

100

arm 6 thereof projects at the same oblique angle relatively to the frame in either position.

As before stated, the fixtures are made up in rights and lefts, and the fixture which is the left hand fixture, as for instance in Figure 4, when applied to the left hand edge face of the sash, becomes the right hand fixture as seen in Figure 5, when applied to the front face of the right hand member of the window frame, and likewise, the right hand fixture becomes the left when it is applied to the front face of the sash, instead of the right edge face of the sash. When the fixtures are applied to the sash in either of said positions, the curtains can be looped back and hung over the arm 6, as shown in Figure 1.

If desired, in order to avoid all liability of the curtain blowing loose from the arm 6, means may be provided for securing them to the arm 6. As best seen in Figures 2 and 3, this means consists of a flexible strand or cord 12 anchored in any suitable manner to the inner end of the arm, and having means as a hook 14 at its outer end for attachment to the arm through a hole 15 in the outer end of the arm. The strand or cord 12 is shown as secured to a coupling member or link 16 mounted coaxially with the pivot 7, the pivot 7 being formed with openings in its ends, and the coupling 16 having inturned ends extending into said openings. When the brackets are not in use, the arms may be folded upwardly along side of the window frame, as shown in dotted lines in Figures 1, 6 and 7.

This curtain fixture is particularly advantageous in that it can be made up in rights and lefts, and applied either to the front face, or the edge faces of the window sash with the curtain retaining arm projecting at a predetermined oblique angle in either of such positions and hence, is extremely economical to manufacture. Owing to the obliquity of the curtain retaining arm and the adaptability to all conditions, the fixture is highly efficient in use.

What I claim is:

1. A curtain fixture of the class described, comprising a base plate and a curtain holding arm projecting from the base plate at an oblique angle, the base plate being mountable upon the front face of the window frame, or an upright outer edge face thereof, and the arm being arranged to project at an oblique angle relatively to the face of the frame when mounted on one edge face of the frame, and to project at substantially the same oblique angle when mounted on the front face of the frame.

2. A curtain fixture of the class described, comprising a base plate, an arm projecting from the base plate, the base plate being mountable on either the front face of the frame or on the edge face of the frame, and the arm being mounted on the base plate to

project at an oblique angle when the base plate is mounted on the right edge face of the frame, and to project at substantially the same oblique angle in the opposite direction when mounted on the front face of the left hand side of the frame and vice-versa.

3. A curtain fixture of the class described, comprising a base plate, an arm projecting from the base plate, the base plate being mountable on either the front face of the frame or on the edge face of the frame, and the arm being mounted on the base plate to project at an oblique angle when the base plate is mounted on the right edge face of the frame, and to project at substantially the same oblique angle in the opposite direction when mounted on the front face of the left hand side of the frame, and vice-versa, said arm being pivoted to the base on a horizontal axis at an angle to the general plane of the base.

4. A curtain fixture of the class described, comprising a base plate, an arm projecting from the base plate, the base plate being mountable on either the front face of the frame or the edge face of the frame, and the arm being mounted on the base plate to project at an oblique angle when the base plate is mounted on the right edge face of the frame, and to project at substantially the same oblique angle in the opposite direction when mounted on the front face of the left hand side of the frame, and vice-versa, the base comprising an upright plate having a horizontal shelf surface provided with pivot bearings, and said arm being pivoted to said bearings, the axis of the pivot extending at an oblique angle to the general plane of the base.

5. A curtain fixture of the class described, comprising a base plate, an arm projecting from the base plate, the base plate being mountable on either the front face of the frame or the edge face of the frame, and the arm being mounted on the base plate to project at an oblique angle when the base plate is mounted on the right edge face of the frame, and to project at substantially the same oblique angle in the opposite direction when mounted on the front face of the left hand side of the frame, and vice-versa, the base comprising an upright plate having a horizontal shelf surface provided with pivot bearings, and said arm being pivoted to said bearings, the axis of the pivot extending at approximately an angle of forty-five degrees to the general plane of the base.

6. A curtain fixture of the class described, comprising a base plate, an arm projecting from the base plate, the base plate being mountable on either the front face of the frame or the edge face of the frame, and the arm being mounted on the base plate to project at an oblique angle when the base plate is mounted on the right edge face of the frame,

and to project at substantially the same oblique angle in the opposite direction when mounted on the front face of the left hand side of the frame, and vice-versa, the base having an angular extending shelf provided with upwardly extending pivot bearings, and said arm being pivoted to said bearings, the axis of the pivot extending at an oblique angle to the general plane of the base.

7. In a curtain fixture of the class described, the combination of a base plate attachable to a window frame, an arm pivoted at one end to the base plate and extending therefrom, when in horizontal position, at an oblique angle, and capable of assuming a vertical position when folded against the window frame.

In testimony whereof, I have hereunto signed my name at Syracuse, in the county of Onondaga and State of New York, this 8th day of September, 1931.

LESTER C. KIENZLE.
